(57) **CLAIM**

The ornamental design for a two conductor electrical cable, as shown and described.

DESCRIPTION

FIG. 1 is a top, side, left end view showing my new ornamental design for two conductor electrical cable;

FIG. 2 is a side view thereof;

FIG. 3 is an end view thereof; and,

FIG. 4 is a top view thereof, the bottom view being identical therewith.

The cable is shown broken-away in the views to indicate indeterminate length.
